CLAIM

The ornamental design for a shower pole caddy, as shown and described.

DESCRIPTION

FIG. 1 is a front perspective view of a shower pole caddy in accordance with my new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom view thereof.

The rear elevational view of the shower pole caddy is not shown in the drawings or described in the specification and, therefore, forms no part of the claimed design.
